UNITED STATES PATENT OFFICE

1,971,396

CEMENTABLE SUPPORT FOR WALL
FIXTURES

Hal De Waide, Portland, Oreg.

Application June 2, 1933, Serial No. 674,000

7 Claims. (Cl. 248—20)

The object of my invention is to provide inexpensive simple and convenient means for attaching a wall cabinet to a room wall, without having to deface the latter.

5 I attain my object in providing a support adapted to be fastened to the wall by being fastened in place by a cementitious plastic compound which dries relatively quickly; said support being provided with simple means for fastening the cabinet to it.

In its broad conception, my support may consist of a body, or disc, having radially disposed openings thru which the cementitious compound will squeeze and form anchoring elements fastening the disc to the wall; the disc being adapted to have incorporated therewith the cabinet fastening means.

20 In another, possibly preferred conception of my support, the same comprises a disc having punched out projecting anchoring tongues which become embedded in the cementitious plastic compound.

25 In still another conception, my support comprises a disc having a hollow section, from which projecting anchor-tongues are punched out, projecting into, and being embedded in the cementitious plastic compound filling said hollow, thus firmly fastening the support to the room wall.

30 As one example of cementitious plastic compound which may be used for affixing said disc in place, I suggest the material sold on the market as "Plastic wood" consisting of wood fiber in a solution of liquid celluloid. Alcohol is a ready solvent for this material and readily softens it after it has set and become solid.

35 Therefore to remove my support it is only necessary to again soften the cementitious plastic compound. Thus my support may be affixed to, and removed from the wall without any defacement of the latter; the wall surface where my disc was affixed being readily cleaned with said solvent.

40 The construction and use of my invention is 45 hereinafter fully described with reference to the accompanying drawing, in which:

Fig. 1 shows a fragmentary front elevation of the ends of a cabinet fastened to a room wall by my support, the front wall of the cabinet being broken away so as to show portions of its rear wall, and illustrates the mode in which the cabinet is fastened in place;

Fig. 2 shows a cross section on the line 2—2 of Fig. 1;

55 Fig. 3 shows a front elevation, partly in sec-

tion of my cementable support of the type shown by Figs. 1 and 2;

Fig. 4 shows a section on the line 4—4 of Fig. 3;

Fig. 5 illustrates another type of my support: As here shown it comprises a disc having 60 punched-out holes thru which the cementitious plastic compound will squeeze and form anchoring elements fastening the disc to the wall;

Fig. 6 shows a central cross section of Fig. 5;

Fig. 7 shows another type of my support: As 65 here shown it comprises a disc having radial punched-out projecting anchor tongues leaving holes in the disc, whereby the cementitious plastic compound by which the support is fastened to a wall is squeezed thru said holes and forms 70 anchoring elements in which said tongues are embedded; and

Fig. 8 shows a central cross section of Fig. 7.

I have described my invention as applied for supporting the cabinet of a roll paper dispenser 75 of the type described in my application for patent which will mature in Letters Patent June 6, 1933, under No. 1,912,363. Such application however, of course, is merely a matter of convenience in describing my invention.

80 My support comprises a metal body or disc 1, having a hollow raised or hemispherical section 2 provided with a perimetric flange 7, and further provided on its under side, thus within the hollow of said section 2, with inwardly projecting 85 anchor-tongues 3 punched out of said section. The raised hollow portion 2 of the disc may be provided with a hole 4 in which to receive a bolt 4a having a nut 6. The rear side of the rear wall 8a of the cabinet 8 is provided at its ends 90 with concavities, or inwardly recessed portions 9, in which to receive my supports, as illustrated in Fig. 2, in which w indicates a room wall section. Said recessed portions of the rear wall of the cabinet are provided with holes 12 thru which 95 bolts 4a extend, and the cabinet is secured in place by nuts 6 threaded on said bolts.

As apparent from the description of my support, its anchor-tongues 3 are embedded in the cementitious compound 10 by which the support is secured to the wall w. Thus the support is firmly and rigidly held in place, and in turn firmly holds the cabinet fastened to my supports.

100 Since my support is cemented to the wall by a compound which may be softened again by applying to it the proper solvent, as mentioned, the removal of my support from the wall will leave the latter without defacement.

105 The openings 11, resulting from the anchor-tongues 3 being punched out of the raised section 110

of the disc, facilitate the application of the solvent to soften the cementitious compound when my support is to be removed.

In the type of my fixture support illustrated by Figs. 5 and 6 the disc 14 is provided with radially disposed holes 15, and has a punched-out central socket 16 adapted to receive the head of a screw bolt 17, on which threads a nut 17a. In securing this disc to a room wall, the plastic compound will be squeezed thru the holes 15 and thus form the anchoring element on the outer face of the disc securing the latter to the wall.

In the type of my invention illustrated by Figs. 7 and 8 the disc 18 has punched-out anchor tongues 19, leaving openings 20. The central portion of the disc is provided with a socket 21 to receive the head of a screw bolt 22, on which threads a nut 22a.

In affixing the latter type of my support on a wall, the plastic compound will squeeze thru the holes 20 and thus form the anchoring element on the outer face of the disc, in which anchoring element the tongues 19 become embedded, thus rigidly securing my support to the wall.

In the use of the types of my wall fixture support illustrated by Figs. 5 and 6, the rear wall of the cabinet would be adapted to receive the fixture, as for example illustrated by Fig. 2.

I claim:

1. A cementable support for wall fixture comprising, a disc provided with radially disposed holes whereby the cementitious plastic compound applied in fastening the disc to a wall is caused to squeeze thru said holes and form anchoring elements, and means for fastening a wall fixture to said support.

2. A cementable support for wall fixture comprising, a disc having punched out radially disposed anchor tongues whereby the cementitious plastic compound applied in fastening the disc to a wall is squeezed thru the holes produced by said punched out tongues, and form an anchoring element embedding said tongues, means for fastening a wall fixture to said support.

3. A cementable support for wall fixture comprising, a disc having a raised hollow section and therein projecting anchoring tongues punched out of said section, whereby the cementitious plastic compound applied in fastening said disc to a wall is squeezed thru the holes produced by said

punched out tongues, thus filling said hollow and forming an anchoring element embedding said tongues, means for fastening a wall fixture to said support.

4. A cementable support for wall fixture comprising, a disc having a raised hollow section and therein projecting anchoring tongues punched out of said section, whereby the cementitious plastic compound applied in fastening said disc to a wall is squeezed thru the holes produced by said punched out tongues, thus filling said hollow and forming an anchoring element embedding said tongues, said hollow section of the disc having a central hole to receive a bolt.

5. In a wall fixture the combination of a support comprising a disc provided with radially disposed holes, said disc being fastened to a room wall by a cementitious plastic compound squeezed thru said holes and forming the anchoring elements of said disc, and a wall fixture whose rear wall is adapted to accommodate said support thus locating said fixture close to the room wall, and means for securing said fixture to said support.

6. In a wall fixture the combination of a support comprising a disc having punched out radially disposed anchoring tongues, said disc being fastened to a room wall by a cementitious plastic compound squeezed thru the holes produced by said punched out tongues and forming the locking element of said disc, and said tongues being embedded in said element, and a wall fixture whose rear wall is adapted to accommodate said support thus locating said fixture close to the room wall and means for securing said fixture to said support.

7. In a wall fixture the combination of a support comprising a disc having a raised hollow section, and therein projecting anchor tongues, said disc being fastened to a room wall by a cementitious plastic compound squeezed thru the holes produced by said punched out tongue and forming the anchoring element of said disc and said tongues being embedded in such element, and a wall fixture whose rear wall is provided with recesses adapted to accommodate said support thus locating said fixture close to the room wall and a bolt provided on said support projecting thru the rear wall of said fixture securing the latter to said support.
